MICROPHONE HOUSING

Roland D. Roesch, La Crescenta, William R. Warren,
Burbank, and Roland G. Ghriest, Rolling Hills, Calif.

Application September 8, 1958, Serial No. 52,554

Term of patent 7 years

(Cl. D26—14)

Fig. 1 is a front elevational view of a microphone housing showing our new design;

Fig. 2 is a side elevational view as it appears from the right-hand side of Fig. 1;

Fig. 3 is a side elevational view as it appears from the left-hand side of Fig. 1;

Fig. 4 is a back elevational view; and

Fig. 5 is a top plan view.

The dominant features of our design reside in the portions shown in full lines. The broken line fragmentary showing of a support in Fig. 2 is for illustrative purposes only, and has been omitted from the remaining figures for convenience in illustration.

We claim:

The ornamental design for a microphone housing, as shown and described.
